WALLPAPER HANGING APPARATUS

Ted R. Wynn, Birmingham, Ala.

Application May 23, 1951, Serial No. 227,866

6 Claims. (Cl. 216—6)

1

This invention relates to wall paper hanging apparatus and more particularly to a device for automatically applying an even layer of paste to wall paper and then applying the paper to a wall or ceiling.

A more specific object of my invention is to provide paper hanging apparatus embodying a paste container, an endless belt mounted for rotation with a portion thereof below the surface of the paste in the container and means to bring a sheet of wall paper in contact with the belt thus applying an even coat of paste to the wall paper.

A further object of my invention is to provide paper hanging apparatus which shall include means for wetting the paper prior to applying the paper to the wall or prior to applying the paste to the paper.

A further object of my invention is to provide apparatus of the character designated which shall include improved means for trimming the paper prior to applying the paste thereto.

A still further object of my invention is to provide apparatus of the character designated having a handle adapting the apparatus for use in any operating position, such as on a wall or ceiling of a room.

Apparatus embodying features of my invention is illustrated in the accompanying drawings, forming a part of this application in which:

Fig. 1 is a perspective view of the apparatus with the belt removed and a portion of the handle omitted;

Fig. 2 is a plan view thereof;

Fig. 3 is a view taken generally along the lines III—III of Fig. 2;

Fig. 4 is a plan view of the handle section removed from the paste applying section of the device as it would be used to wet a roll of wall paper;

Fig. 5 is a view taken along the line V—V of Fig. 4;

Fig. 6 is a fragmental plan view showing the rotary cutters employed to trim the paper; and

Fig. 7 is an elevational view of the apparatus being employed to paper the ceiling of a room.

Referring now to the drawings for a better understanding of my invention, I show a frame indicated generally by the numeral 10. The frame comprises side walls 11 and 12 spaced apart by a paste container 13. The paste container is formed of a substantially U-shaped sheet of metal and comprises longitudinally extending vertical walls 14 and 15 and a relatively narrow bottom 17. The edges of the U-shaped sheet of metal

2

are secured to the side walls 11 and 12 as at 18 so as to provide a water tight container. It will be apparent that the container 13 may have end walls secured to the side walls 11 and 12 or the side walls may serve as the end walls, as shown in the drawings.

The side walls 11 and 12 slope forwardly and downwardly from the tops thereof as at 19 and forwardly and upwardly from the bottom thereof as at 21 for a purpose to be explained later. Slots 22 and 23 are provided in the forwardly and downwardly sloping portions 19 of the side walls 11 and 12 respectively for receiving the reduced ends 24 and 26 of a roller 27. The roller 27 is of a size to fit snugly in a roll of wall paper 28 and rotatably support it between the side walls 11 and 12. One end of the roller 27 is provided with a substantially square depression 29 for a purpose to be described later.

20 Rotatably mounted between the side walls 11 and 12 in openings 31 and 31a is a rotary cutter 33 and rotatably mounted between the side walls in openings 32 and 32a is a rotary cutter 34. The rotary cutter 33 comprises a rod 36 having

25 spaced sleeve members 37 and 38 non-rotatably mounted thereon by means of set screws 39. The rotary cutter 34 comprises a rod 41 having rotatably mounted thereon sleeve members 42 and 43. Secured to the outer faces of the sleeve

30 members 42 and 43 are disc members 44 and 46, respectively. Surrounding the rod 41 and positioned between the wall 11 and the disc 44 is a compression spring 47 and surrounding the rod 41 and positioned between the wall 12 and the disc 46 is a similar compression spring 48. The compression springs 47 and 48 bias the disc members 44 and 46 toward the outer faces of the sleeve

35 members 37 and 38 thus providing means for severing the wall paper as it passes between the disc members and the sleeve members 37 and 38.

Positioned within the paste container and secured to the lower portion of the side walls 11 and 12 are bearing bosses 49 and 51. Extending between the side walls 11 and 12 and rotatably

45 mounted in the bearing bosses 49 and 51 is a roller 52. Rotatably mounted in openings 53 and 54 in the side walls 11 and 12 above the roller 52 and above the paste container 13 is a roller 56 having a diameter approximately twice that of the roller 52. The rollers 52 and 56 are preferably made of metal such as steel. Passing over the rollers 52 and 56 is an endless belt 57 formed of a water absorbent material such as cloth.

Extending between the side walls 11 and 12 and in position to contact the belt 57 at a point

beneath the roller 56 and above the paste container 13 is a roller 58. The roller 58 and the rotary cutter 33 are so positioned that a sheet of paper passing around the cutter 33 and between the roller 58 and the belt 57 will contact the upper edge of the vertical wall 14 of the paste container 13. The upper edge of the wall 14 is concavely curved as at 59. By concavely curving the upper edge of the wall 14, the paper is held accurately aligned on the roller as it passes thereover.

The side walls 11 and 12 project outwardly adjacent the top thereof as at 61 and 61a. Rotatably mounted between the projecting portions on a shaft 30 is a presser roller 62 made of a resilient material such as rubber. The shaft is rotatably supported in openings 65 and 65a provided in the projecting portions. The upper edge of the vertical wall 16 extends upwardly and outwardly as at 63 thus returning to the paste container 13 any drippings from the rollers 56 and 62.

Pivoted to the frame 10 is a handle member 67 including a substantially U-shaped steel rod 68 terminating in inwardly extending ends 64 and 66 which fit into depressions or sockets 69 and 71 respectively, provided in the ends of the shaft 60. The legs of the U-shaped portion of the handle are of a length for the handle to swing 360° about its pivot point and clear all corners of the side walls 11 and 12. By sloping the side walls as at 19 and 21 ample clearance is obtained with a relatively short handle.

Secured to the rod 68 by any suitable means such as by welding is a V-shaped brace rod 72. The free ends of the V-shaped rod 72 are in the form of bearing members or loops 73 and 74 which are positioned on opposite legs of the U-shaped rod so that a plane passing through both of the loops is substantially parallel to the inwardly extending ends 64 and 66, as clearly shown in Fig. 4 of the drawings. The loops 73 and 74 are spaced from each other a distance slightly greater than the length of the roller 27.

When the device is used to wet a roll of wall paper the end 24 of the roller 27 is rotatably supported in the loop 73. The other end 26 of the roller 27 is rotatably supported by means of a crank 75 which extends through the loop 74 and detachably fits in the square depression 29, as shown in Fig. 4.

Extending between the base of the U-shaped rod 68 and the bottom of the V-shaped rod 72 and lying substantially normal to the base of the U-shaped rod is a wooden handle proper 76 having longitudinally extending grooves 77 and 78 on each side thereof. The handle proper 76 is held in place by means of rods 79 and 81 which fit in the grooves 77 and 78 and are secured to the rod members 68 and 72 by any suitable means such as by welding.

Secured to the bottom of the V-shaped member 72 adjacent the outer end of the wooden handle member 76 is a bracket 82 which lies in a plane substantially normal to a plane passing through both legs of the V-shaped member 72. Rotatably mounted at the outer end of the bracket 82 is a roller 83. The bracket 82 and the roller 83 serve to hold the handle proper 76 away from the wall 84 as the paper is being applied thereto.

From the foregoing description, the operation of my improved paper hanging apparatus will be readily understood. In order to obtain an even coat of paste on the paper, I first wet the

paper. To wet the paper, the handle section 67 is removed from the frame 10. The end 24 of the roller 27 is inserted in the loop 73 and the crank 75 is inserted through the loop 74 into the opening 29 thus rotatably supporting the roller 27 between the loops. The ends 64 and 66 of the rod 68 are moved apart a sufficient distance to permit a roll of wall paper 28 to be inserted therebetween and be rotatably supported by the ends 64 and 66. The end of the sheet of wall paper is then passed over the roller 27 and secured thereto so as to cause the paper to wind about the roller 27 as the crank 75 is turned. The roll of paper 28 is then placed in a receptacle containing water. As the crank 75 is turned the paper is wound about the roller 27, thus permitting the entire surface of the sheet of paper to come in contact with the water.

After wetting the paper the roller 27 having the paper wound thereon is inserted in the slots 22 and 23. From the roller 27 the paper passes between the rotary cutters 33 and 34 where the paper is trimmed as it passes between the sleeve members 37 and 38 and the disc members 44 and 46. The sheet of paper next passes over the concavely curved portion 59 of the wall 14 and then under the roller 58. As the paper passes over the concavely curved portion 59 the paper is aligned as described above. The sheet of paper passes from under the roller 58 over the belt 57 and the roller 56 then under the presser roller 62 onto the wall to be papered.

As the device is moved downwardly over the wall, the paper causes the belt 57 to rotate thus continuously applying an even coat of paste to the paper. By wetting the paper prior to applying the paste thereto, there are no dry spots left on the surface of the paper and an even and smooth coat of paste is obtained over the entire surface of the paper. I have also found that prewetting of the paper prevents the same from cracking when it dries.

To apply the paper to the ceiling of a room the handle is swung to a position approximately 90° from that employed to apply paper to a wall. As shown in Fig. 7 of the drawings, the container 13 is thus kept in an upright position while the roller 83 contacts the wall.

My apparatus is equally adapted for use in applying paper which has a dried film of glue thereon. In order to apply such paper to a wall, the container 13 is filled with water. The paper is then caused to move through the device as described above. As the paper moves over the wet belt 57 the glue on the paper dissolves thus permitting the paper to be applied to the wall as the device is moved downward over the wall.

While I have described the wall paper as being prewet prior to applying paste thereto, it will be apparent that my improved apparatus may also be employed to apply a coat of paste to a dry sheet of paper.

From the foregoing it will be apparent that I have devised an improved paper hanging device which is simple of construction and very economical of manufacture. By providing a detachable handle which may be employed to wet the roll of wall paper prior to applying the paste thereto and one which will swing 360° about the apparatus, a very flexible and easily operated device is obtained. Also, by providing a device which is adapted both for use in applying paste to the wall paper or for use in wetting paper having a dry film of glue applied thereto, a very useful device is obtained.

While I have shown my invention in but one form, it will be obvious to those skilled in the art that it is not so limited but is susceptible of various changes and modifications without departing from the spirit thereof, and I desire therefore that only such limitations shall be placed thereupon as are specifically set forth in the appended claims.

What I claim is:

1. In paper hanging apparatus, laterally spaced side walls, a paste container mounted between said side walls, a rotatable member mounted for rotation between said side walls with a portion thereof extending down into the paste container, a slot in the upper forward edge of each side wall, a roller rotatably mounted in said slots for supporting a roll of wall paper and delivering the same to said rotatable member, a presser roller rotatably mounted between said side walls in position to receive the paper after it has passed over said rotatable member, sockets in each end of said presser roller, a U-shaped rod having inwardly projecting ends detachably fitting in each of said sockets, a bearing member secured to each leg of the U-shaped rod intermediate the ends thereof adapted for rotatably mounting a roller therebetween in a plane substantially parallel to said inwardly projecting ends, and means to rotate said roller mounted in said bearings to wind paper thereon from a roll of wall paper rotatably supported between said inwardly projecting ends.

2. Apparatus as defined in claim 1 in which the legs of the U-shaped rod are spaced apart a distance slightly greater than the distance between the laterally spaced side walls and are of a length to clear all corners of said side walls.

3. Apparatus as defined in claim 1 in which the means to rotate the roller mounted in said bearings comprises a crank extending through one of said bearing members and detachably secured to one end of said roller mounted in said bearings.

4. In paper hanging apparatus, laterally spaced side walls, a paste container mounted between said side walls, a roller rotatably mounted between said side walls adjacent the bottom of the paste container, a second roller rotatably mounted between said side walls above said paste container, a water absorbent belt passing over said rollers, means to pass a sheet of wall paper over and in contact with said belt, a presser roller rotatably mounted between said side walls in position to receive the paper after it has contacted said belt, a substantially U-shaped rod terminating in inwardly projecting ends pivotally mounted to opposite ends of said presser roller,

an outwardly projecting handle adjacent the base of the U-shaped rod, a bracket secured to the outer end of the handle and extending outwardly therefrom in a direction substantially normal to a plane passing through both legs of the U-shaped rod, and a roller mounted for rotation adjacent the outer end of the bracket.

5. In paper hanging apparatus, laterally spaced side walls, a relatively deep and narrow paste container mounted between said side walls, a roller rotatably mounted between said side walls adjacent the bottom of the paste container, a second roller positioned above said paste container and rotatably mounted between said side walls directly above said first mentioned roller, a water absorbent belt passing over said rollers, means to pass a sheet of wall paper over and in contact with said belt, a presser roller detachably mounted for rotation between said side walls in position to receive the paper after it has contacted said belt, a handle frame member for the apparatus, and a handle proper secured to said frame member.

6. In paper hanging apparatus, laterally spaced side walls, a relatively deep and narrow paste container mounted between said side walls, a roller rotatably mounted between said side walls adjacent the bottom of the paste container, a second roller positioned above said paste container and rotatably mounted between said side walls directly above said first mentioned roller, a water absorbent belt passing over said rollers, means to pass a sheet of wall paper over and in contact with said belt, a presser roller between said side walls in position to receive the paper after it has contacted said belt, a handle member having inwardly projecting ends, there being openings in the side walls adjacent the ends of the presser rolls for receiving said inwardly projecting ends of the handle member, and sockets in each end of said presser roller receiving said inwardly projecting ends, said presser roller being rotatable about said inwardly projecting ends.
